UNITED STATES PATENT OFFICE.

LEVI L. FUNK, OF CHICAGO, ILLINOIS.

FORMING-TOOL.

1,122,720.

Specification of Letters Patent.

Patented Dec. 29, 1914.

Application filed April 2, 1913. Serial No. 758,475.

To all whom it may concern:

Be it known that I, LEVI L. FUNK, a citizen of the United States, and a resident of Chicago, in the county of Cook and State 5 of Illinois, have invented a certain new and useful Improvement in Forming-Tools, of which the following is a specification.

This invention relates to tools for forming sheet metal articles, and relates particularly to a tool designed for forming 10 copes used in dentistry to cover the roots of the teeth in inserting false teeth by means of pivots.

The object of the invention is to provide 15 a tool by means of which sheet metal articles, as for example, dental copes and the like, may be made in the laboratory quickly and economically.

To this end, a tool of my invention comprises the various features and details of construction hereinafter described and claimed.

In the accompanying drawing, in which my invention is fully illustrated, Figure 1 is a side view of my improved tool; Fig. 25 2 is a top plan view thereof; Figs. 3 and 4 are fragmentary views of my improved tool, illustrating the manner of using same for forming copes, the outer member of same being shown in longitudinal section and 30 the inner member in side elevation; Fig. 5 is a plan view, on an enlarged scale, of a blank adapted for forming the cope; and Fig. 6 is an enlarged view of a finished article.

35 My improved tool consists of coöperating dies, comprising an inner male die 1 and an outer female die 2, said female die 2 being slotted at its end, and the male die 1 being pivoted in said slots, substantially in the 40 manner of a pair of forceps or pliers. As the dies 1 and 2 are opened and closed, the end of the male die is adapted to pass through the slot in the female die 2, the end of said slot being closed, as clearly shown 45 in Fig. 2, and the opening in said female die conforming to the shape of the end of the male die 1, and both conforming to the shape of the finished article, sufficient clearance being left between the sides of the 50 male and female dies to receive the metal for forming said cope or other article. Formed in the side of the male die which is adjacent to the female die when said dies are in open position, is a slot 3 which is 55 adapted to receive a sheet metal blank, as

the blank 4 (Fig. 5) for forming the cope 5 (Fig. 6), or other article, said slot 3 being formed at such an angle that when the front end of said slot is flush with the sides of the female die, the rear end of said slot 60 will be slightly above and outside of said female die, thus progressively drawing the blank into desired form, so as to distribute the work of drawing said blank to form the finished article, and rendering the tool easy 65 to operate. Preferably, also, the relation is such that when said dies are fully closed, the male die will have passed through the female die so that the slot 3 and the formed article held therein will be exposed at the 70 rear side of the female die, thus providing for removing the finished article before retracting said male die.

The manner of operating my improved tool is as follows, particular reference being 75 had to Figs. 3 to 6 of the drawing, in which I have shown the manner of using my improved tool for forming copes for dental use: The blank 4 is inserted into the slot 3 with the jaws substantially in the position 80 shown in Fig. 3, so that it will project symmetrically at the sides of the male die 1. The male and the female dies are then closed, to bring the projecting portions of the blank into contact with the edges of 85 the female die 2, further movement of said male die operating to bend the projecting edges of said die upwardly, as shown in Fig. 4. When said dies are in fully closed position, as shown in dotted lines in Fig. 90 4, the slot 3 and blank 4 are entirely beneath the female die 2, thus providing for removing the shaped blank from said slot before again opening said dies, the shape of said blank, when removed, being substantially 95 as shown in Fig. 6, in which the finished cope 5 is shown. It will be understood that this particular use of my improved forming tool is illustrative merely, as said tool is adapted for a wide range 100 of application. Neither do I desire to limit myself to the particular construction shown.

With the tool as heretofore described, it is obvious that the side of the blank which is inserted into the slot 3 will be flat, and to provide for bending or drawing down the flat side of said article, in case it is desired to flange same on all sides, I provide a projection 6 at the extreme end of the back of the male die 1, the outer side of 110

said projection being coincident with and conforming in shape to the end of said male die 1.

The cope or other article having been flanged on three sides by means of my improved tool, is removed therefrom, and is placed on the top of the projection 6 with its unflanged side projecting over the outer end thereof, the projecting edge thereof being hammered or pressed down by means of a suitable instrument, as a hammer. Also, if desired, my improved tool may be readily adapted for thus flanging the flat edge of said cope or other article by merely providing a removable pivot pin for said male die, thus providing for readily detaching said male die and for reversing same to bring the projection 6 thereon into operative relation with the female die 2. Having thus reversed said male die, said cope or other article is placed on said projection 6 with its edge projecting as before, and is forced through the female die, thus flanging the flat edge thereof in the manner desired. As shown in the drawings, means are provided for thus detaching and reversing said male die, said means consisting merely in providing a pivot pin 7 adapted to be secured in screw-threaded engagement with an opening in a side of the female die 2. To provide for conveniently screwing up and unscrewing said pivot pin, wings 8 are preferably provided on the head end thereof, thus providing for conveniently grasping said screw with the thumb and finger for the purpose of turning the same.

I claim:

1. Dies for forming sheet metal articles, comprising a female die provided with a hole which extends through the same and a male die adapted to pass through the opening in said female die, said dies being provided with clearance between their co-operating surfaces, and said male die being provided with a slot adapted to receive and hold a sheet metal blank, substantially as described.

2. Dies for forming sheet metal articles, comprising a male and female die provided with clearance between their co-operating surfaces, and said male die being

provided with a slot adapted to receive and hold a sheet metal blank, said slot extending at an angle to the upper surface of said female die when the advanced side of said slot is flush therewith, substantially as described.

3. Dies for forming sheet metal articles, comprising a male and female die provided with clearance between their co-operating surfaces, and said male die being provided with a slot adapted to receive and hold a sheet metal blank, the relation being such that when said dies are in closed position, the shaped article in said slot will be below the female die, substantially as described.

4. In a tool for forming sheet metal articles, the combination of pivotally connected members, comprising handles for operating the same, a female die on one member provided with a hole which extends through the same and a male die on the other member adapted to pass through the hole in said female die, said dies being provided with clearance between their co-operating faces, and said male die being provided with a slot adapted to receive and hold a sheet metal blank, substantially as described.

5. In a tool for forming sheet metal articles, the combination of pivotally connected members comprising handles for operating the same, a male die formed on one of said members and a female die on the other member, said dies being provided with clearance between their co-operating faces, and said male die being provided with a slot adapted to receive and hold a sheet metal blank, and a projection on the rear side of said male die, the outer side of which substantially coincides with and conforms to the shape of said male die, substantially as described.

In testimony that I claim the foregoing as my invention, I affix my signature in presence of two subscribing witnesses this 29th day of March, A. D., 1913.

LEVI L. FUNK.
